CLAIM

The ornamental design for a wipes bottle cap, as shown and described.

DESCRIPTION

FIG. 1 is a top and front perspective view of a wipes bottle cap, showing my new design with the lid in the closed configuration;

FIG. 2 is a bottom and front perspective view thereof;

FIG. 3 is a front elevational view thereof;

FIG. 4 is a rear elevational view thereof;

FIG. 5 is a side elevational view thereof;

FIG. 6 is another side elevational view thereof;

FIG. 7 is a top plan view thereof;

FIG. 8 is a bottom plan view thereof;

FIG. 9 is a top perspective view thereof, with the lid open;

FIG. 10 is a front elevational view thereof, with the lid open;

FIG. 11 is a rear elevational view thereof, with the lid open;

FIG. 12 is a side elevational view thereof, with the lid open;

FIG. 13 is another side elevational view thereof, with the lid open;

FIG. 14 is a top plan thereof, with the lid open; and,

FIG. 15 is a bottom plan view thereof, with the lid open.
